HANGER FOR A PICTURE OR MIRROR

Joseph M. Margulis, % Jiffy Enterprises, Inc.,
150 N. 13th St., Philadelphia, Pa.

Filed May 2, 1962, Ser. No. 69,935

Term of patent 14 years

(Cl. D17—12)

FIGURE 1 is a side elevational view of a hanger for a picture or mirror showing my new design;

FIGURE 2 is a front elevational view thereof;

FIGURE 3 is a back elevational view thereof;

FIGURE 4 is a back sectional elevational view taken along lines 4—4 of FIGURE 1;

FIGURE 5 is a bottom plan view thereof;

FIGURE 6 is a side sectional elevational view taken along lines 6—6 of FIGURE 2; and

FIGURE 7 is a perspective view thereof.

My design is characterized by a square base and a hook extending from a bottom and top horizontal plane of the base in a continuous arc to a point above the top horizontal plane of the base, the arc above the base top plane being of a length substantially equal to and overlying the length of the arc between the bottom and top base plane,

the arc above the top base plane terminating in a square face located in a vertical plane, all as shown.

I claim:

The ornamental design for a hanger for a picture or mirror, as shown and described.
